UNITED STATES PATENT OFFICE

WILLIAM E. ELLING, OF LONG ISLAND CITY, NEW YORK

FOLDABLE OR COLLAPSIBLE BOAT

Application filed July 21, 1931. Serial No. 552,098.

This invention relates to improvements in collapsible or foldable boats, particularly such as described in my co-pending application, Serial No. 508,654, filed January 14th, 1931, and it is the principal object of my invention to provide means allowing the construction of an inexpensive collapsible boat which is watertight when unfolded and particularly useful as a lifeboat, or as a boat to be used on hunting or fishing expeditions as its construction allows the ready installation of an outboard motor, and the convenient storing of the boat in a garage or carrying it on the running board of an automobile.

Another object of my invention is the provision of a collapsible or foldable boat, the walls of which are to bend conveniently to useful curves, yet possess the necessary stability or stiffness when the boat is unfolded.

Still another object of my invention is the provision of a collapsible or foldable boat which may readily be used as pontoon for aircraft of every description and which can be readily folded and stored when not to be used.

Further objects of my invention are to be seen in the provision of foldable fins stiffening the boatwalls, which may, moreover, form foldable airtanks on such foldable or collapsible boats, as they are for instance disclosed in my co-pending application identified above, and in the provision of improved hinge constructions for connecting the parts of a watertight folding boat structure allowing a ready folding of the boat and producing a watertight closure between the parts connected by said hinges.

Still further objects of my invention are the provision of a collapsible or folding boat equipped with folding thwarts, seats and beams co-operating with its other parts to facilitate the opening and collapsing operation and acting as braces for the unfolded boat, and of easily bendable guards or stiffeners for collapsible or foldable boats which are preferably made of a plurality of wooden strips, or may be made of metal or similar suitable material and are arranged in superposition and provided with elongated holes

for permitting engagement by the fastening means.

These and other objects and advantages of my invention will become more fully known as the description thereof proceeds, and will then be specifically defined in the appended claims.

In the accompanying drawings forming a material part of this disclosure:

Fig. 1 is a perspective view of a folding or collapsible boat constructed according to my invention.

Fig. 2 is a central section through the boat, Figure 1, unfolded.

Fig. 3 is a section similar to Figure 2 showing the boat in the process of folding.

Fig. 4 is a fragmentary sectional view illustrating the connections between boat wall and transom.

Fig. 5 is a detail side elevation of the connection clamp illustrated in Figure 4.

Fig. 6 shows the foldable seat of the boat, Figure 1, in opened condition.

Fig. 7 shows the floor of a collapsible boat rolled up.

Fig. 8 is a fragmentary side elevation of a boat floor with a girder and cut outs for stiffening fins.

Fig. 9 is an enlarged sectional view through a collapsible air chamber of a boat with bottom and side wall on the outside thereof.

Fig. 10 is a side elevation of a part of a boatwall with a plurality of stiffening fins in their folded position.

Fig. 11 is a side view of Figure 10 with the fins unfolded.

Fig. 12 is a sectional view of a bendable stiffening clamp attached to the wall of my collapsible boat.

Fig. 13 is a fragmentary sectional view of the side wall of a collapsible boat showing the connection of the bendable stiffening clamp Figure 12 and the connection and lock of a foldable seat.

Fig. 14 illustrates two collapsible boats connected by hinged braces to an airplane, and diagrammatically the folding of the sides and the seat of a boat.

Fig. 15 is a sectional view through a boat,

Figure 14 illustrating the cables leading to the cockpit of an airplane.

Figs. 16 to 23 illustrate in detail sectional elevations a plurality of hinge constructions 5 which I use with my collapsible boat.

As illustrated in Figures 1 to 8, the preferred and most useful form of my collapsible boat consists of two side parts 18, 17, and a bottom made in two parts 19, 20, hinged 10 together by means of a hinge 21, while the curved edges of the side walls are hingedly connected to the curved edges of the bottom by means of hinges 22, of any desired type for instance such as described hereafter.

15 Foldable stiffening fins designated 23, 24, curved homogeneous to the curvature of side and bottom, are hingedly connected to the side walls 17, 18, and partly forming the plank sheer. Also hingedly connected to 20 the side walls are two fins 25, 25', to which each end of an extension of the foldable seat having bevelled inner edges 26, 27, is loosely connected by means of the clips 29 which are fastened to the seat halves and adapted to 25 overlap and hold said fin. A bolt 28, connects the inner meeting ends of the two seat parts 26, 27, while the bevelled outer ends of these seat parts engage the bevelled edges of the extensions and are held in place by means 30 of the catch 30.

Two fins 31, 32, and a cover 33, are hinged- 35 ly connected amongst themselves and to each side wall and form a watertight airchamber when the boat is unfolded and end covers 34, 35 34' hingedly connected to the side wall close the chamber and are secured by clamps, while the lower fin 32 is extended to the ends of the boat.

40 Stiffening longitudinally extending fins 35 are hingedly connected to the bottom, while floor laths 36, are laid crosswise on top of said fins 35, and are connected by flexible strips 38, and girders 37, to fit between fins 35, are fastened to laths 36.

45 The end piece or transom 39, has a layer of felt 40, attached at ends and bottom, and in addition on both sides a plurality of clips 41, and continuous hinges 42, 42', have one of their leaves attached to the boat wall and 50 their other leaves to the end piece 39. Fingers 43 on the hinge leaves on end piece 39 are engaged by the lower bent end flanges of channel shaped clamps 46, the upper ends of which engage clips 41 with their bent ends 55 47, thus, pulling the end piece 39 and the boat-walls together and pressing the upright hinge leaves against the layer of felt 45 which is held between the hinges 42, 42', and the boat-walls, while pins 48 passing through 60 openings in clips 41 and the slots 48' are provided to hold the clamps 46 in place.

A modified construction of an air chamber is shown in Figure 9, and consists of two foldable fins 49, 49', hingedly connected to 65 the side wall 50 and bottom 50', respective-

ly, two cover plates 51, 52, are hingedly connected to the fins 49, 49', and at their meeting point 53.

A part of a boatwall 55 is illustrated in Figure 10, equipped with a plurality of 70 hingedly connected curved metal strips 56 in folded condition; Figure 11 shows the boat wall and said strips unfolded.

As illustrated in Figures 12 and 13, a modified wall stiffening clamp consists of a plurality of longitudinally arranged laths 60 held together by bolts 57, which are securely fastened to the boatwall 58 by nuts 59 and 75 counternuts 59', and the laths 60, have elongated holes 61 to take the bolts 57.

80 Figure 13 shows the end of a seat I, with a modified form of connection to the side wall 58 according to which a slot socket II is fastened to the sidewall, a hinge part III to suit socket II is connected by another hinge part 85 IV to the seat, a pin V, extending from under the seat is fastened to the seat and will go thru a hole in part III and thereby act as a lock.

85 As shown in Figures 14 to 15, two collapsible boats are connected to an airplane by hinged braces 62, 62', 63, 63', 64, 64', pivotally connected to the top edges of the sides 65, 65', the sides are hingedly connected to the bipartite bottom 66, 66', which has a hinge 90 along its centerline 67, a foldable seat 68, is hingedly connected as at 69 to the top edge of the sides 65, 65', and at its centerline 70, its parts are hingedly connected. The boat is covered by canvas 71, fixedly connected to the 100 side walls, the cables 72, 72' are firmly connected to the side walls and run through a pair of blocks 73, 73' before passing through the boat cover to the cockpit of the airplane.

105 Another cable 74 is firmly connected to the center of the seat at 70, and passes through a block at 75, before leading to the cockpit of the airplane, another pair of cables 76, 76', are firmly connected to the outside of the bottom 66, 66'.

110 In Figures 16, 17, 21, and 22, I have illustrated, modified constructions of hinge connections between side walls 77 and the bottom 78 of a collapsible boat which are watertight when opened up to 90°. Figure 16 shows 115 an all metal hinge with two inner parts 79, 80, to form the hinge and two outer parts 81, 82, to overlap one another and press the overlapping ends of felt layers 83, 83' against each other, and part 82 is bent out from the pin 84 to allow a folding of the walls and bottom.

120 Figure 17 shows the side wall 85 and the bottom 86 made of wood with an ordinary piano hinge 87 on the inside layers of felt 88, 88' are guided around the edges of the boat bottom and walls, and two metal strips 89, 90, are attached to side and bottom respectively, overlapping each other, so that part 90 will 125 press into felt 88' thus insuring a watertight closure, in addition thereto, the bottom and 130

wall parts 85, 86, will press against each other. Figure 21, shows a construction similar to Figure 17, but parts 95, 95' are straight with a diagonally arranged part 96 to press against felt layers 94, 94'. The construction of Figure 22 will act in a manner similar to Figure 21, it shows side wall 97 and bottom 98 made of thin material and has two finger-shaped parts attached to the hinge parts 101, 101' with a part 102 between to press into layers of felt 103, 103' which holds layers of rubber or similar material 104, 104'.

In Figures 18, 19, 20, and 23, I have illustrated various forms of connections between the halves of the bottom of a boat along its center line.

As shown in Figure 18, the bottom halves 105, 105' are connected by means of a hinge 106, the leaves of which are bent upon themselves, as at 107, 108, and have curved overlapping ends, and a layer of felt 108', rubber or similar material is interposed between the hinge leaves and their parts 107, 108, with its center part pressed into the curve formed by the overlapping ends. It will be clear that a watertight closure will thus be provided between the inner ends of the bottom halves when they form an angle of 180°.

As shown in Figure 19 the bottom halves 109, 109' are connected by a hinge 111, and a strip 110 of felt or other suitable material is interposed between one of the hinge leaves and bottom part 109'. To the outside of either bottom half are attached two strips 112, 113, having their inner ends bent out of the plane of the strips and overlapping at their meeting point when the bottom parts are unfolded, while cushions of soft compressible material 114 are interposed between the bent parts of strips 112, 113, or the bottom halves. It will be clear that a watertight closure will thus be provided when the bottom parts assume an angle of 180°.

In Figure 23, the bottom halves 115, 116, are made of wood or similar material and held together by an ordinary continuous hinge 117, a metal strip 118, held in a groove in bottom half 115 is adapted to engage with its outer end in an opposite groove in 116, and two metal strips 119, 120, fastened and overlapping each other are attached to the top of the bottom halves, while layers of felt 121, 122, in the groove of 116 and at the end of strip 118 engaging therein are engaging each other and are held engaged by strips 119, 120, and hinge 117 when the bottom halves assume an angle of 180°. The part 115 has a shoulder formed in its inner end adapted to be engaged by the inner end of strip 120.

In Figure 20 is shown a simple connection of the bottom halves 123, 124, which are bent at their meeting ends to form interengaging hooks for holding layers of felt, rubber or similar material 125, 125', engaged to be

pressed inwardly by the edges of the bottom parts, a plurality of brackets 126 attached to the lower bottom part 124 and a plurality of wedges 127 are arranged to wedge and hold said finger-shaped bottom parts together and ensure a watertight closure. 73

In operation and actual construction it will be observed:

The hingedly connected stiffening fins will have to be fastened to the boat wall on a curve homogeneous to the curve desired for the boat wall after unfolding same. 75

They have to be fastened with the rounded edges to the inside of the boat and with the concave edge to the outside of the boat. I 80 may partly cover the boat as shown in Figure 1 with canvas to avoid water or spray coming in.

While it is easy to see for instance in Figure 3 how the fin 25 is in position to take 85 the seat, of course, the bottom will have to be flattened first before opening the sides.

While the seat in Figure 14 is shown only diagrammatically as it would be impossible to show it on the folded boat as it would show 90 among the braces 62, 63 and 64.

It will be clear that foldable fins may be also used at the underside of the bottom on collapsible boats for use in ice regions which will then act as sled runners. 25

Each of the fins will fold flat to the wall to which it is hingedly connected. The connected edge of a fin used on a collapsible boat must conform to the curve of the wall when boat is unfolded. 100

It will be understood that I have disclosed the preferred forms of my invention only, as a few examples of the many possible ways to practically construct my invention, and that I may make such changes in the general arrangement and combination of parts, as well as in the construction of the minor details thereof, as come within the scope of the appended claims without departure from the spirit of my invention and the principles involved. 105

Having thus described my invention what I claim as new is:

1. A collapsible and portable boat comprising a bipartite rigid bottom, a continuous metal hinge connecting the parts of said bottom at center-line, curved sides, and continuous metal hinges connecting the sides to the bottom parts, means to make the seams in way of hinges watertight, a portable end piece at one end of the boat, clamping means to hold and watertighten this end piece, a foldable seat, locking means for seat connections to side walls, longitudinal clamps made of several strips of stiff, yet bendable material laid one on top of the other, and bolts passing through elongated holes in said strips for fastening said clamps to the walls of the boat. 110

2. A collapsible, portable boat comprising 115

- a bipartite rigid bottom, a continuous watertight metal hinge for connecting the parts of said bottom at center-line, curved sides, continuous watertight metal hinges connecting said sides to the bottom parts, a removable end piece at one end of the boat, clamping means to hold and watertighten this end piece, between the sides and to bottom, a foldable seat, stiffening fins on the inside of the boat, means connecting said seat to said fins, continuous stiffening fins hingedly connected to the inside of the side walls for acting partly as a plank sheer, continuous stiffening fins hingedly connected to the outside of the side walls to act partly as spray-board and guard, other hingedly connecting fins, a cover interconnecting said fins and end pieces to form air chambers on the boat walls, and a means constituting the floor of the boat.
3. In collapsible, portable boats of the class described, continuous foldable fins of suitable width and rigid yet flat bendable material, and a means for attaching said fins to the boat walls, said means forming part of a continuous metal hinge.
4. In collapsible, portable boats of the class described, continuous foldable fins of suitable and rigid yet flat bendable material, and a means for attaching said fins to the boat walls, said means constituted by an ordinary continuous hinge, or a plurality of hinges.
5. In collapsible boats of the class described, a means of forming air tanks when boat is unfolded comprising two fins, hingedly connected to the boat walls, a cover plate hingedly connected to the outer edges of the fins, means to make the seams in way of hinges watertight, two end covers hingedly connected to the boat walls, and clamping means to hold and watertighten said end covers.
6. In collapsible boats of the class described, a means of forming air tanks when boat is unfolded comprising two fins hingedly connected to side and bottom, two cover plates hingedly connected to the outer edge of said fins, parallel to side and bottom and hingedly connected at their meeting point, means to make the seams in way of hinges watertight, end covers, and clamping means to hold and watertighten said end covers.
7. In collapsible boats of the class described, a foldable seat or brace to act as means for assisting in opening the boat, comprising two halves to fold into each other, a bolt running thru each part to act as a hinge, two members hingedly connected to each end of the seat, two elements attached to the sides of the boat having slots to engage said last named hinge parts, and locking means to hold the seat in straight, folded condition.
8. In a collapsible boat, a means for clamping the transom of a boat to its side walls and bottom, comprising two hinge elements attached to the boatwalls fore and aft of transom, a layer of felt between said hinge elements and transom, two fingers having bent upper ends connected to said hinge elements, a plurality of finger-parts fastened to both sides of the transom, a plurality of conical channel-shaped clamps having bent fingers on both sides to engage said finger parts, a pin for each clamp passed through one of a plurality of holes through upper fingers, and a layer of felt around outer edge of transom.
9. A means for making the floor in a collapsible boat and enabling said floor to be rolled up to a bundle, comprising a plurality of stiffening fins hingedly connected to the floor, and longitudinal laths on said fins, and cross-laths, flexible straps for connecting said cross-laths parallel to each other, and resting on top of said foldable fins of the bottom of the boat, a girder fastened underneath and at centerline of each cross-lath with "cut-outs" for the reception of stiffening fins and longitudinal laths.
10. In collapsible boats of the class described, a means for making the boat walls, said means comprising a plate of suitable watertight material, a plurality of strips formed homogeneous to the desired curve of side edge of plate and hingedly connected to said plate in longitudinal direction at alternate positions for stiffening said plate when unfolded.
11. In collapsible boats of the class described, a means for making bendable longitudinal clamps comprising several strips of stiff, yet bendable material laid one on top of another having elongated holes and bolts passed through said holes for fastening said clamps to the boat walls.
12. A collapsible foldable boat, comprising a bi-partite rigid bottom, a continuous watertight metal hinge connecting the parts of said bottom at centerline, curved rigid sides, continuous watertight metal hinges connecting said sides to the bottom parts, a flexible top, fixedly connected to the top edge of the sides, a collapsible brace hingedly connected to the top edge of the sides of the boat, a means for connecting said boat to the underside of an airplane, a means permitting folding and unfolding of said boat including cables leading to the cockpit of the airplane.
13. A watertight continuous hinge for connecting the sides to the bottom of a collapsible boat when opened to 90° comprising a hinge element connected to the hinge pintle, the opposite hinge element set about $1\frac{1}{4}$ of its thickness off the pintle, a third member integral with said first named hinge element and curved at the under edge according to the radius of action, a piece of felt entered between and filling part of the space formed thereby, a fourth member integral with said

second hinge element curved to suit said space and adapted to press into the felt to ensure a watertight closure.

14. In a collapsible boat, a means for connecting the sides of the boat with its bottom, comprising two layers of felt laid around the rounded edges of side wall and bottom, and pressing against each other when the boat walls are unfolded, an ordinary hinge connection at the inside, and according to the radius of action two curved metal strips attached to the outside of bottom and side wall, one of said strips adapted to press into said layer of felt for ensuring a watertight closure.

15. A watertight hinge for connecting the bottom halves of a collapsible boat, when opened to 180° comprising an ordinary continuous hinge, composed of two straight elements bent upon themselves and leaving a space, a felt filler in said space, two interfilling curved parts at the ends of said elements, one of which presses upon said filler, said curved parts sliding freely upon each other as the hinge joint is flexed.

16. A watertight hinge construction for connecting the bottom halves of a collapsible boat comprising an ordinary continuous hinge to connect the bottom halves, a strip entered between one bottom half and said hinge, the bottom halves overlapping each other, two straight elements having offset fingers at their inner ends attached to either bottom half and overlapping each other at centerline, two pieces of felt covering the inner faces of said hinges and held on either side by said last named elements and by said hinge, and a body of soft material entered and held by said pieces of felt in space formed between said fingers.

17. A watertight joint construction for connecting the bottom halves of a collapsible boat comprising two bottom plates with channels along their centerline, a layer of felt in each channel, a plurality of bracket fastened to the inside of the lower plate, and a plurality of wedges engaged to press the channels one into another.

18. In collapsible boats, a means for connecting the sides of the boat with its bottom and make the seam watertight, comprising layers of felt around the rounded edges of side wall and bottom, an ordinary hinge connection on inside, two flat continuous elements on the outside of said wall and bottom, and a third continuous member adapted to press against the felt of the wall ends.

19. A watertight continuous hinge for connecting the sides to the bottom of a collapsible boat when opened to 90° comprising an ordinary continuous hinge, two elements attached to the outside of each hinge part and having fingers almost touching at their meeting points, two felt layers held by said ele-

ments and filling the spaces between, and a loose part when unfolded automatically pressing against the felt.

Signed at New York, in the county of New York and State of New York, this 20th day of July, A. D. 1931. 70
